US0D1033750S

(12) United States Design Patent (10) Patent No.: US D1,033,750 S
(45) Date of Patent:  Jul. 2, 2024

(54) HEADGEAR

(71) Applicant: Chuangang Luo, Jiayu (CN)

(72) Inventor: Chuangang Luo, Jiayu (CN)

() Term: 15 Years

(21) Appl. No.: 29/835,873

(22) Filed: Apr. 22, 2022

(51) LOC (14) Cl. 29-02

(52) U.S. Cl.

USPC D29/108

(58) Field of Classification Search
